UNITED STATES PATENT OFFICE

2,602,293

IGNITER PORT VALVE MECHANISM FOR
COMBUSTION CHAMBERS

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application February 7, 1948, Serial No. 7,019

4 Claims. (Cl. 60—39.82)

1

This invention relates to combustion chambers particularly adapted for use in rockets and propulsion apparatus. The invention relates more specifically to combustion chambers having igniters of the hot-flame type, such as are disclosed in the prior Goddard Patent #2,090,039, issued August 17, 1937.

It is desirable that such igniters have no communication with the combustion chamber except when they are in actual operation. This separation of the igniter from the chamber prevents flash-back, overheating of the igniter, and the accumulation of combustion residue or deposits in the igniter when not in operation.

It is the general object of the present invention to provide a port in the combustion chamber to admit an igniter flame, and to further provide improved valve mechanism for normally closing the port and for opening the port only for igniter operation.

The invention further relates to arrangements and combinations of parts which will be herein-after described and more particularly pointed out in the appended claims.

Preferred forms of the invention are shown in the drawing, in which:

Fig. 1 is a sectional elevation of a portion of a combustion chamber, with one form of this invention applied thereto;

Fig. 2 is a perspective view, partly in section, of the valve member shown in Fig. 1; and

Fig. 3 is a sectional view similar to Fig. 1 but showing a modified construction and certain control devices.

Referring to Figs. 1 and 2, a front end portion of a rotating combustion chamber C is shown, together with an axially positioned igniter G which is assumed to be of the hot-flame type, one example of which is more fully disclosed in the prior Goddard patent above cited.

The chamber C is provided with an axial port 10, normally closed by a valve member 12. The member 12 has a tubular outward extension 14 and is normally forced upward to closed position by a spring 16, the upper end of which engages a collar 17 threaded on the upper end of the valve part 14. The collar 17 is freely slidable in a bushing 20 fixed in the lower end of a tube or sleeve 21 which is mounted on the chamber C concentric with the igniter port 10, and which rotates with said chamber. At its outer end, the sleeve 21 has a thrust bearing 22 to resist the reactive thrust of the rotating chamber C.

The valve member 12 has a series of ports 25 55 Engagement of the contact members 63 and 64

2

in its tubular extension 14 and adjacent the enlarged lower end of the member 12, and also has an internal flange 26 which supports an anti-friction bearing plate 27 positioned for engagement by the lower end of the igniter G.

When the igniter is to be put in operation, the igniter is forced inward (or downward in Fig. 1), engaging the plate 27 and forcing the valve member 12 inward to the dotted line position shown in Fig. 1. In this position, the ports 25 in the valve portion 14 are freely open to the combustion chamber C, so that the ignition flame will enter the chamber in a series of dispersed jets which are exceptionally effective for rapid ignition of the combustion mixture in the chamber C.

As soon as pressure is relieved on the igniter G, the igniter will be raised by a spring 28, and the valve 12 will return to closed position. The igniter may be advanced and released manually, or automatic control mechanism of the general type shown in Fig. 3 may be provided.

With this construction, it will be seen that the igniter has no communication with the chamber C except when depressed to operative position, which construction is found very desirable, as previously explained.

In the construction shown in Fig. 3, an igniter G' is mounted in fixed position in alignment with a port 40 in a stationary combustion chamber C'. This port is normally closed by an inwardly opening valve 42 mounted on an arm 43 which is pivoted at 44 to a bracket 45 projecting outward from the chamber C'.

When the igniter G' is to become operative, the valve 42 is moved to the dotted line position shown in Fig. 3 by a solenoid S operating through a plunger 50 and link 51. When the solenoid S is inoperative, the valve 42 is raised and closed by a spring 53.

A simple form of control mechanism is also shown in Fig. 3, by which the operation of the valve 42 and the igniter G' may be coordinated, and by which the operation of the igniter may be discontinued as soon as a sufficiently hot flame has been projected through the port 40.

The operation is started by manually depressing a handle 60 on a lever 61 pivoted at 62 and having a contact point 63 which engages a second and fixed contact member 64 when thus depressed. A ledge 65 on the lever 61 is then engaged by a latch 66 which is pivoted at 67 and which is moved to latching position by a spring 68.

closes circuits from a battery B (or other suitable source of current) through the solenoid S previously described, and also through a sparkplug 70, and through a solenoid 71 which depresses a plunger 72 and thus opens a fuel mixture valve 73 for the igniter G'. The port valve 42 is thus opened inward, while at the same time the fuel mixture is admitted through the valve 73 and is ignited by the sparkplug 70.

A control device 75 containing a thermo-couple is mounted on the chamber C' and projects slightly into the path of the hot flame from the igniter G'. When the thermo-couple is thus heated, the couple is closed, thus completing a circuit from a battery B' through a solenoid 80, which solenoid acts through a plunger 81 to withdraw the latch 66 from the flange 65.

The lever 61 is then drawn upward by a spring 82, raising the contact point 63 and breaking the circuits through the solenoids S, the sparkplug 70, and the solenoid 71. The valve 73 will then be closed by the spring 83 and the valve 42 will be closed by the spring 53, while at the same time the sparkplug 70 becomes inoperative. All parts will remain in the closed or inoperative positions indicated until further operation of the igniter G' is desired.

Having thus described the invention and the advantages thereof, it will be understood that the invention is not to be limited to the details herein disclosed, otherwise than as set forth in the claims, but what is claimed is:

1. In combustion apparatus, a combustion chamber having an igniter port, a valve to close said port, a flame-type igniter aligned with said port, electro-magnetic means to move said valve inward to open said port, yielding means to close said port, a fuel-supply valve for said igniter, electro-magnetic means to open and close said fuel-supply valve, a single electric power circuit in which said two electromagnetic means are mounted in parallel, and means to close said cir-

cuit, whereby said port-opening means and said fuel valve-opening means are simultaneously activated.

2. In combustion apparatus, a combustion chamber having an igniter port, a valve to close said port, a flame-type igniter aligned with said port, yielding means to close said port, means to render said igniter operative when said valve is moved inward, and means to release said valve when a flame of predetermined temperature has been injected through the igniter port.

3. In combustion apparatus, a combustion chamber having an igniter port, a valve to close said port, a flame-type igniter aligned with said port, a solenoid to move said valve inward to open said port, a latch to hold said valve open, and temperature-controlled means to withdraw said latch and release said valve when a sufficiently hot flame has been injected through said port.

4. The combination in combustion apparatus as set forth in claim 3, in which a supply valve and sparkplug for said igniter are mounted in parallel to said solenoid and are jointly held closed by said latch.

ESTHER C. GODDARD,
*Executrix of the Last Will and Testament of
Robert H. Goddard, Deceased.*
